(57) **CLAIM**

We claim, the ornamental design for a tubular holder for a medical injector, as shown and described.

DESCRIPTION

FIG. 1 is a top right perspective view of a tubular holder for a medical injector;

FIG. 2 is a bottom left perspective view thereof;

FIG. 3 is a right-side perspective view thereof;

FIG. 4 is a left-side perspective view thereof;

FIG. 5 is a left-side elevation view thereof, the right-side elevation view being a mirror image thereto;

FIG. 6 is a top elevation view thereof, the bottom elevation view being a mirror image thereto;

FIG. 7 is a top plan view thereof; and,

FIG. 8 is a bottom plan view thereof.

1 Claim, 7 Drawing Sheets
